TUMBLER OR SIMILAR ARTICLE

Carl J. Uhrmann, Bellaire, Ohio, assignor to Imperial Glass Corporation, Bellaire, Ohio, a corporation of Ohio

Application March 5, 1951, Serial No. 14,383

Term of patent 14 years

(Cl. D36—8)

To all whom it may concern:

Be it known that I, Carl J. Uhrmann, a citizen of the United States, residing at Bellaire, county of Belmont, and State of Ohio, have invented a new, original, and ornamental Design for a Tumbler or Similar Article, of which the following is a specification, reference being had to the accompanying drawings, forming a part hereof, in which:

Figure 1 is a side elevational view of a tumbler or similar article showing my new design, the figure illustrating substantially a 120° surface area of the same;

I claim:

The ornamental design for a tumbler or similar article, substantially as shown and described.

CARL J. UHRMANN.
